UNITED STATES PATENT OFFICE.

ALBERT S. HOWELL, OF CHICAGO, ILLINOIS, ASSIGNOR TO BELL & HOWELL COMPANY,
OF CHICAGO, ILLINOIS, A CORPORATION OF ILLINOIS.

DEVICE FOR CLEANING FILMS.

1,237,047.

Specification of Letters Patent. Patented Aug. 14, 1917.

Application filed November 27, 1916. Serial No. 133,768.

To all whom it may concern:

Be it known that I, ALBERT S. HOWELL, a citizen of the United States, and a resident of the city of Chicago, county of Cook, 5 and State of Illinois, have invented certain new and useful Improvements in Devices for Cleaning Films, of which the following is a specification.

My invention relates to devices for cleaning film and more particularly to an apparatus adapted to dust and clean cinematographic film after it leaves the machine that has cut the marginal perforations therein.

One of the objects of my invention is the provision of a film cleaning device that will utilize the advantages of a rotary brush cleaner and a pneumatic or suction cleaner, so that all dust and minute particles will be removed from the surface of the film and 20 after removal will be drawn away therefrom. Another object of my invention is the provision of a cleaning device that may be satisfactorily operated in conjunction with a film perforating machine and which 25 may be readily attached thereto. Still another object of my invention is the provision of a film cleaning device through which the film may be easily threaded. Further objects of my invention are the provision of a 30 film cleaning device that is constructed of a minimum number of parts, with a maximum of efficiency; that is easy to manipulate; and is a comparatively inexpensive accessory to a film perforating apparatus.

I prefer to accomplish the divers objects of my invention by substantially the means and in the manner hereinafter fully described and as more particularly pointed out in the claims, reference being had to the 40 accompanying drawings forming a part of this specification, wherein,—

Figure 1 is a longitudinal side elevation of my film cleaning device detached from the film perforating machine.

Fig. 2 is a top plan of my invention.

Fig. 3 is a horizontal longitudinal section taken on line 3—3 of Fig. 1.

Fig. 4 is a longitudinal vertical section of a fragmentary portion of my invention taken 50 on line 4—4 of Fig. 2.

Fig. 5 is a vertical end elevation of my device.

Referring to the drawings, wherein similar reference characters are employed to des-

ignate the same parts throughout the figures, 55 it will be observed that my film cleaning device preferably comprises a suitable hollow shell or casing, one end portion 10 whereof is substantially cylindrical in cross-section, while the opposite end portion or barrel 11, 60 which communicates and is joined therewith, is substantially elliptical in cross-section and is closed at its outer end by a transverse end wall 12. The elliptical portion 11 forms a housing within which the 65 brushes rotate, as will hereinafter more fully appear, and has its end wall 12 and top and bottom walls provided with a continuous elongated slot 13 for the purpose of facilitating the threading of the film 70 edgewise into the device and its transit therethrough. The slot is slightly widened as at 14, 14, in the central portions of the top and bottom walls and suitable wipers 15, 15, are mounted so as to partially close these 75 widened openings. Said wipers 15 are preferably made of strips of felt or other similar soft fibrous material, that are laid parallel to each other upon opposite sides of the slot and are clamped between the leaves 80 of suitable clamps or holders 16, 16, by screws 17, or in any other suitable manner.

The barrel 10 is substantially the same diameter as the minor axis of the elliptical housing 11 and is adapted to carry the bearings of the brush shafts. Fitted into this barrel 10 of the casing is a hollow, cuplike internal sleeve 18, the outer end whereof is closed by a transverse wall 19 of slightly greater diameter than said sleeve, to provide a shoulder that limits the distance said sleeve may be inserted into the barrel 10. Two bearing bosses 20, 20, are provided upon the interior of the wall of the sleeve 18, the axes whereof are disposed parallel 90 with each other and in the same horizontal plane. Suitable rotatable shafts 21, 21, are mounted in said bearings and are extended beyond both the inner and the outer ends thereof, the inner ends of said shafts being 100 internally screw-threaded and have the threaded ends of brush spindles 22, 22, screwed therein. The brushes 23, 23, that are carried by these spindles 22, are of the ordinary type of rotary brushes comprising 105 a plurality of radially disposed bristles and are of such diameters that the peripheries thereof will overlap each other, as shown

clearly in Figs. 3 and 5 of the drawings, so as to extend into the path of the film passing through the housing.

The outer ends of shafts 21 extend 5 through the wall or plate 19 and are provided with pinions 24, 24, that mesh with each other and are adapted, when driven, to rotate their respective shafts in opposite directions. One of said shafts 21 is slightly 10 longer than the other so that its outer end will extend through its pinion where a suitable drive pulley 25 is rigidly secured thereto.

In operation, it is desired to feed the film 15 from the perforator upwardly through the widened portions 14 of the slots 13 and between the brushes and to rotate the latter so that the peripheries thereof adjacent the film will be moving downwardly in a direction opposite to the line of travel of the film, so that the latter will be thoroughly brushed 20 and all fine particles removed therefrom. In order to remove fragments of celluloid produced by the perforation of the film, 25 and all foreign matter from the surface of the film where it might subsequently, during the development, cause the specking or spotting of the film, I have attached to the casing, preferably at the aperture 26 in the 30 barrel, 10, an exhaust or suction pipe 20, which creates a current of air flowing into the casing through slots 13 adjacent the surface of the film and out of the casing through said aperture 26. This current of 35 air serves to remove from the film and out of the casing all particles detached either by the current of air or by the brushes from the surface of the film.

I prefer to secure the sleeve 18 within the 40 barrel 10 by means of a knurled headed thumb-bolt 27, the shank whereof passes through an open slot 28 and is screwed into the adjacent portion of the sleeve 18. The slot 28 is cut in from the outer end of the 45 barrel 10 and a shallow, circular depression or seat 29 is made in the surface of the barrel surrounding the inner end of the slot, as shown, so that the boss of said thumb-bolt will engage and seat in the same when 50 turned down tightly into place, thereby preventing any relative movement of the sleeve when the device is in use. It will also be observed that by loosening the thumb bolt 27 so that its boss will be disengaged from 55 the depression or seat 29, the sleeve 18 upon which the bearings 20 are mounted, together with shafts and rotatable brushes 23, may be removed longitudinally or axially out of the barrel 10. This is desirable for the purpose 60 of renewing or adjusting the brushes or for cleaning out the interior of the casing.

I have herein disclosed specific instrumentalities for carrying out my invention, and have described the device in connection 65 with a film perforating apparatus, but it

will be obvious that it may be used at any time it is desired to clean film for cinematographs, as well as other kinds of material, and divers modifications are possible without departing from the spirit of my invention. It is therefore to be understood that all such changes are contemplated as included within the scope of my invention as expressed in the appended claims.

What I claim is:

1. A cleaning device comprising a suitable housing, brushes rotatable therein, a barrel extended from and communicating with said housing, bearings in said barrel for said brushes, and means whereby said brushes are rotated in opposite directions. 75

2. A cleaning device comprising a suitable housing, brushes rotatable therein, a barrel extended from and communicating with said housing, an internal sleeve mounted in said barrel, and bearings carried by said sleeve adapted to journal the spindles of said brushes. 80

3. A cleaning device comprising a suitable housing, brushes rotatable therein, a barrel extended from and communicating with said housing, an internal sleeve mounted in said barrel provided with oppositely disposed longitudinally extended bearings, parallel shafts rotatable in said bearings the inner ends whereof are secured to said brushes, and means operatively connecting said shafts whereby the same are rotated simultaneously in opposite directions. 90

4. A cleaning device comprising a suitable housing provided with a vertically disposed passageway for the transit of film, wipers disposed upon opposite sides of the entrance to said passage, brushes rotatable within said housing the peripheries whereof overlap each other and extend across the plane of said passageway, a barrel extended from said housing having bearings therein for said brushes, and means adapted to rotate said brushes in opposite directions. 100

5. A cleaning device comprising a suitable housing provided with means for the passage of film therethrough, brushes rotatable within said housing the peripheries whereof overlap each other, wipers mounted on said housing adjacent said brushes, a barrel extended from said housing, an internal sleeve fitted in said barrel, parallel horizontally disposed bearings disposed in said sleeve, shafts journaled in said bearings the inner ends whereof carry said brushes, pinions upon the outer ends of said shafts in mesh with each other, and means for actuating said pinions. 115

6. A cleaning device comprising a shell, 125 brushes rotatable therein, rotatable shafts upon which said brushes are mounted, bearings for shafts mounted in said shell and removable with said brushes from said shell, and means for actuating said shafts. 130

7. A cleaning device comprising a suitable housing, brushes rotatable therein, a barrel extended from said housing, rotatable shafts journaled in said barrel upon which said brushes are mounted and which are removable therefrom with said brushes, and means for actuating said shafts.

Signed at Chicago, county of Cook and State of Illinois, this 16th day of November, 1916.

means for actuating said shafts.

8. A cleaning device comprising a suitable housing, a barrel extended from said housing, brushes rotatable in said housing, shafts upon which said brushes are mounted, bearings in said barrel in which said

shafts are journaled and which, together with said shafts and brushes, is removable from said barrel, and means for actuating 15 said shafts.

Signed at Chicago, county of Cook and
State of Illinois, this 16th day of November,
1916.

ALBERT S. HOWELL.
